CASH REGISTER, ACCOUNTING, AND THE
LIKE MACHINEErnst Breitling, Berlin-Tempelhof, Germany, as-
signor to The National Cash Register Company,
Dayton, Ohio, a corporation of MarylandApplication October 5, 1935, Serial No. 43,731
In Germany January 7, 1935

5 Claims. (Cl. 235—138)

The invention relates to cash registers, accounting and the like machines and more particularly to tens transfer devices of such machine especially when the machines are provided with an add and subtract or balance totalizer in which the tens carrying is effected stepwisely and the fugitive "one" added by a second revolution of the carry mechanism actuating shaft.

10 The main object of the invention is to reduce the number of transfer cycles and thus increase the time available for each single tens transfer operation in a machine operation of any kind or mode.

15 Another object of the invention is to provide means effective in all denominational orders in each moment of the tens transfer and carrying time period.

Another object of the invention is to adapt 20 and arrange the carrying means in any or some of the denominational orders to delay tens carrying to a certain extent of the time period available.

Further objects of the invention will be pointed 25 out in the following detailed description with reference to the annexed drawings.

A preferred form of an embodiment of the invention is shown in the annexed drawings.

Of said drawings:

30 Fig. 1 is a cross section in side elevation of the machine showing an amount key bank, the differential device and other means connected therewith.

Fig. 2 is a transverse section in top view of 35 the balance totalizer,

Fig. 2a is a detail view of a part of the "fugitive 1" mechanism shown in Fig. 2,

40 Figs. 3a to 3c show cross sections through the balance totalizer taken along line II—II of Fig. 2, with the tens transfer and carrying device in different working positions,

Figs. 4a to 4c are part views of the balance totalizer with the transfer mechanism carrier in positions corresponding to those in Figs. 3a to 3c,

45 Fig. 5 is a side view of the transfer mechanism carrier on an enlarged scale.

Fig. 6 (a to c and a' to c') show diagrams of three examples of tens transferring and carrying performed with the old device and with the novel 50 device in amount entering actions,

Figs. 7 and 8 illustrate modified forms of driving pinions for the transfer actuating mechanism.

General description

55 The tens transfer mechanism according to

the present invention relates to devices of the type in which, in the various denominational orders, tens transfers are prepared by the machine operation during adding or subtracting operations, and completed after such operations. 5

More particularly, the invention consists in providing means, especially in each denominational order of an add and subtract or balance totalizer, adapted to operate carrying means in any moment of the time available for tens transfer and to add also the fugitive "one" when a passage from "9" to "0" occurs in the highest denominational order in subtract operations. 10

In known totalizers tens carryings prepared after amounts are entered, are executed by an 15 actuating shaft actuated by the machine drive, and having arranged thereon a one-tooth disk in each denominational order. As in any denominational order in which the adding wheel was set to "9", a tens transfer impulse will cause 20 an additional tens transfer to be rendered effective, tens carrying has to be started from the lower order advancing stepwise up to the highest. For this reason the carrying disks fast on the actuating shaft are disposed thereon in such 25 a way that their transfer teeth are arranged to form a helical line and, thus, become effective after one another beginning at the next to the lowest denominational order.

The actuating shaft runs idle till the disk associated with the first denominational order in which tens carrying is prepared, becomes effective, whereupon all prepared tens carryings are performed in next higher denominational orders after one another. When in balance totalizers the sign of the total is changed with the highest denominational order passing from "9" to "0", a tens carrying in the lowest denominational order is caused and effected thereby 40 adding the fugitive "one". As the transfer teeth of all the disks have already passed their effective ranges, another revolution of the actuating shaft is required for these carrying operations which possibly have to be continued up to the next 45 higher orders. By this second revolution of the said shaft all the necessary tens carrying—starting from the lowest denominational order—up to the totalizer wheel operated first during the first revolution of the said shaft, are effected, where- 50 after, however, the shaft runs idle through the denominational orders in which tens carrying has already been effected during the first revolution of the shaft. Thus a portion of the one cycle and another portion of the second cycle of 55

the two cycles, that is, a full cycle altogether, is ineffective.

In the device according to the present invention, the disks, as already mentioned, are so shaped, or rather provided with so many teeth, that they offer a tens transfer actuating means in all the denominational orders effective simultaneously throughout the whole tens transfer period.

10 Thereby idle runs are eliminated and, in comparison with the known device, a whole idle revolution is saved.

Detailed description

15 The balance totalizer which has applied thereto a device according to the invention is similarly constructed to the one set forth and described in U. S. A. Patents 1,839,138 and 2,052,444.

20 The key board of such a machine comprises eight amount key banks and several special key banks to select totalizers for deposit entries, as well as totalizers for withdrawal entries. A further key bank controls positive and negative old balances. Further, the key board comprises a 25 motor key, a balance or total lever and a mode of operation or machine conditioning lever. The latter can be set to four positions, viz: "Addition", "Subtotal", "Grand total" and "Duplicate". The machine as shown in Fig. 1 contains a row of 30 nine totalizers for the positive entries and another row of nine totalizers for the negative entries. Furthermore, a third row comprising six totalizers is provided which serve, respectively, to accumulate the positive and negative old balances, 35 the deposits and withdrawals, and the positive and negative new balances.

35 In the fourth row the balance, or add and subtract totalizer, is arranged which comprises (Figs. 1, 2, 3a) in each denominational order two 40 counting wheels, an adding wheel 1 and a subtracting wheel 2. The hub 3 of each adding wheel 1 has fast on it a pinion 4 which is in mesh with another pinion 5 fast on a hub 7 mounted on a shaft 6. The hub 7 has further fast on it a pinion 8 in mesh with a broad pinion 10 fast on a shaft 9. Pinion 10 is further in mesh with a pinion 11 fast on the hub 12 of the subtracting wheel 2. Upon one of the two counting wheels 1 or 2 being driven, a rotation of the same amplitude but in opposite direction is imparted to the other counting wheel.

45 The counting wheels 1, 2 are further provided with internal teeth which may be engaged by riders 14 secured to necks of the shiftable rider 50 shaft 13 so as to take part in the axial shifting motion of the latter but freely turn thereon.

The rider shaft 13 can be shifted by means 55 not shown, as they are no part of the present invention, into three positions in which the riders 60 14 are in mesh either with the internal teeth of the adding wheels 1 or with those of the subtracting wheels 2, or with none of them.

65 The counting wheels 1, 2 of each order are mounted on the extended hub 195 of a differential wheel 16 which hub has a longitudinal slot 17 in which the appertaining rider 14 may be shifted. That counting wheel with the internal teeth of which the rider 14 is in mesh, is thus 70 coupled with the differential wheel 16. The latter is actuated in accordance with the depression of the respective amount key 201 of the respective order. Previous to the return of the differential actuators 250, the balance totalizer is coupled with them by rocking it to such an extent 75 that the differential wheels 16 come into mesh

with the tens transfer wheels 19 which are rotatably supported by a carrier 115 which in turn is loosely arranged on shaft 20. The tens transfer wheels 19 are permanently in mesh with the differential actuators 250 by means of intermediate wheels 21 loose on shaft 20.

Now, when in an adding machine operation the differential actuators 250 have been positioned in accordance with the amount keys 201 depressed, and the differential wheels 16 have been 10 coupled with the respective counting wheels, for instance, with the adding wheels 1, by shifting the rider shaft 13, then the coupling of the balance totalizer is effected in a manner not shown, by rocking it into cooperative position, so that 15 the differential wheels 16 come into mesh with the tens transfer wheels 19. In the subsequent return of the differential actuators 250 the differential wheels 16 are turned clockwise according to the position of the differential actuators 20 250. This rotation is transmitted in clockwise direction to the counting wheels coupled with the differential wheels 16, that is, in the assumed case, to the adding wheels 1. The other counting wheels, viz., the subtracting wheels 2 are 25 turned by the same amplitude as the adding wheels proper but in opposite direction, that is counter-clockwise.

30 In subtractive amount entering the rider shaft 13 is shifted to the left to such an extent (Fig. 2) 30 that the riders 14 couple the subtracting wheels 2 with the differential wheels 16. This action is the same as described, with the only difference that the subtracting wheels 2 are turned clockwise and the adding wheels 1 counter-clockwise. 35

35 The rider shaft 13 and the shaft 18 are mounted to shift together. The shaft 18 is provided with an annular groove 22 for each transfer member 23, said members 23 being rotatable in the grooves 22, but they are not shiftable relatively 40 to the shaft 18, so that the teeth 23 always lie opposite the corresponding rider 14 and the coupled counting wheels 1 or 2 respectively. When a passage from "9" to "0" takes place in any order, the tens tooth 1a or 2a of the coupled counting wheel 1 or 2 strikes the companion tens tooth 23 and rocks it counter-clockwise about shaft 18 by 45 degrees. On shaft 18 a tens transfer pinion 25 is loose but not shiftable therewith, and its hub 25a has a recess in which the companion tens 50 tooth 23 is shifted together with shaft 18. The companion tens tooth 23 is connected by a stud 24 to the tens transfer pinion 25 in such a manner that upon shaft 18 being shifted it can slide in the recess of hub 25a, but that a rotation about 55 shaft 18 is performed by both these members in common and to the same extent.

On the left hand front surface of tens transfer pinion 25 a pin 116 is fixed (Figs. 2 and 4a) which projects into a recess 117 of the carrier 115 of the 60 next higher denominational order. The pin 116 cooperates with the boundary surfaces of said recess 117.

The recess 117 possesses two operating and locking surfaces 118, 119 (see Fig. 5) and a top 65 surface 120 extending concentrically with the shaft 20 (Fig. 5) and sliding on shaft 18. Two notches 121, 122 are formed at the ends of surface 120 for shaft 18. In order to avoid self-locking due to friction, the surfaces 118, 119 are 70 subdivided by edges 118a, 119a so as to form two operating surfaces 118c, 119c and two locking surfaces 118b, 119b. The surfaces 118b and 119b are arcuate with centres 118o and 119o which coincide with the center of shaft 18 when it as- 75

sumes its end positions relatively to carrier 115. In order to insure in all events a precise engagement, the rotation of the transfer pinion 25 caused by the tens tooth 1a or 2a serves only as 5 a preparatory movement for the engagement of the pinion 25 with the carrying member 31 (Fig. 3b), whereas the actual carrying caused by the pinion 31 itself is effected by the machine drive common to all the denominational orders at a 10 latter time period.

The mode of operation in tens transfer operations is as follows:—

When in the rest position, the parts assume the position illustrated in Fig. 4a in which the notch 121 (Fig. 5) of the recess 117 engages with the shaft 18 while the pin 116 is located in a notch 123 formed at the upper end of locking surface 118b. Consequently the carrier 115 is locked against rocking motion toward the left by notch 121 and toward the right by the notch 123. Since 20 the surface 118b is drawn with the shaft 18 as center, the circular path of the point of contact 125 of pin 116 lies within the range of the circular surface 118b and the pin 116 may be rocked counter-clockwise about 18. As soon, now, as one of 25 the counting wheels 1 (Fig. 3b) arrives in the zero position or passes therethrough, the tens tooth 1a rocks the transfer member 25 of the next higher order about shaft 18 in counter-clockwise 30 direction into the position illustrated in Figs. 3b and 4b. Thereupon, after completion of the amount entering, in order to effect the tens transfer, all the members 25 in preparatory position 35 are engaged by the carry mechanism actuating pinions 31 of the machine drive and turned farther counter-clockwise by a certain angle corresponding to the advance of one unit (Figs. 3c and 4c). When the pin 116 comes into contact with the operating surface 119c, the carrier 115 40 is rocked thereby until its notch 122 engages with shaft 18. In this extreme position the carrier 115 is locked against motion in both directions by the notch 122 and the pin 116. The return of the displaced pinion 25 especially the 45 tooth 23 to initial position (Fig. 3a) is effected by known means (not shown) toward the end of the machine operation or at the commencement of a new operation with the totalizer disengaged. During the return of the parts to initial position, the pin 116 first leaves the surface 119c and then 50 acts upon the operating surface 118c, whereby the carrier 115 is rocked into initial position (Fig. 4a), and the notch 121 again engages shaft 18. Upon further rotation of the pinion 25 the pin 55 116 comes first into contact with the surface 118b and then enters notch 123.

The carrying pinions 31 which effect the tens transfers which have been prepared in the various denominational orders, are provided according to 60 the invention with as many teeth as the balance totalizer has orders, and thus offers in all denominational orders at the same time a tooth for performing a tens transfer originated in the respective order, so that all the tens transfers in 65 various orders simultaneously originated, are also carried out simultaneously. When in adding, the add or subtract wheel of any denominational order has not passed "9", the tens carrying device is in rest position as shown in Figs. 3a and 4a. When, however, the wheel passes from "9" to 70 "0" the tens tooth 1a, or 2a, rotates the transfer pinion 25 by about 45 degrees into the preparatory position, whereby the tooth 18 comes into the path of the teeth of the carrying wheel 31 (Figs. 3b and 4b). As the carrying pinions 31

are disposed on the shaft 20 in equal distances, each transfer pinion 25 moved into preparatory position, regardless of the denominational order to which it belongs, is rotated further by the first tooth of the wheel 31 into the position shown in 5 Figs. 3c, 4c wherein the intermediate wheel 19 rolls on the arrested wheel 21 and advances the differential wheel 16 and thus the counting wheel 1, and 2 respectively, by one unit.

When, during any tens carrying operation, a 10 tens carry in the next higher denominational order is prepared, the tooth 18 of the tens transfer pinion 25 of this denominational order comes into the reach of the teeth of the carrying wheel 31, whereupon the said pinion 25 is turned by one 15 of the next teeth of the wheel 31 since the first tooth thereof has passed already.

Also the highest denominational order has allotted thereto a tens transfer pinion 25 fixed to shaft 18, while a pinion 25' located before the 20 lowest denominational order is connected by a spring 85 to the shaft 18 (Fig. 2) and cooperates with a carrying pinion 31.

This mechanism is fully illustrated and described in the patent to Breitling, No. 2,052,444, 25 and will be but briefly described herein. On the right-hand end of shaft 18 (Fig. 2) is loosely mounted a sleeve 80 having a longitudinal slot engaged by a pin 81 rigid on shaft 18, so that sleeve 80 does not partake of the shifting motion of 30 shaft 18, but of a rotation thereof. The sleeve 80 has on its left-hand end face a shoulder 82, cooperable with a shoulder 83 of the tens coupling member 25' loose on shaft 18. The member 25' is arranged in front of the lowermost order 35 and carries a pinion 84 rigid with it for a purpose not disclosed herein but described in the above mentioned Patent No. 2,052,444. Between sleeve 80 and pinion 84 is disposed the torsional spring 85 which holds the stop faces 82a and 83a (Fig. 40 2a) of the shoulders 82 and 83 in abutment on one another, while other stop faces 82b and 83b include an angle of 45 degrees which corresponds to the extent of movement of shaft 18 for the tens transfer preparatory movement. When the 45 highest denominational wheel passes from "9" to "0", the shaft 18 is given its preparatory movement to position a tooth 18 opposite the lowest order denomination into mesh with the pinion 31. Thereafter, when this lowest order pinion 31 50 is rotated by the main shaft, the member 25' is given its transfer movement, which, through pin 116 and arm 115, and elements operated thereby, as above described, enters the "fugitive 1" into the lowest denominational order wheel of the 55 totalizer.

When in the highest denominational order the subtract wheel 2 passes from "9" to "0" or the sign of the total on the balance totalizer changes into negative, a tens carrying or adding of the 60 fugitive "one" in the lowest denominational order is effected by the tooth then situated in operative range, of the respective carrying pinion 31.

Fig. 6 shows there examples illustrating the operation of the tens carrying device. The diagrams 6a, 6b, 6c on the left side show the solution of the problems by means of the known successively operating tens carrying device, and the diagrams 6a', 6b', 6c' on the right side the solution effected by means of the device according to 65 this invention. The denominational orders of the balance totalizer assumed, by way of example, to comprise ten denominational orders, are indicated by the numerals 1 to 10 arranged horizontally, the said denominational orders hav- 70 75

ing allotted thereto one carrying pinion each. The vertical lines indicate the timing, and the adding period is intimated by dotted lines in the upper part of each chart, while the efflux of time during which the carrying operations are executed in the denominational orders, is indicated by thicker lines in an enlarged scale comprising the lower portion of each chart. The short thick vertical lines represent the single tens carrying which has been effected in the respective order. The horizontally directed arrows drawn in dotted lines, show the course of the tens carrying impulses between the individual denominational orders.

15 In the first example:

$$0 \text{ minus } 10,000$$

the negative amount 10,000 is entered into the zeroised balance totalizer. At this time the adding wheel (+) and the subtract wheel (−) are adjusted:

$$\begin{array}{r} (+) 0 \ 000 \ 000 \ 000 \\ (-) 9 \ 999 \ 999 \ 999 \end{array}$$

25 Now a "1" is added to the "9" on the subtract wheel of the fifth order. Thereby said wheel passes to "0" and transmits a tens transfer impulse to the next higher (the sixth) order wherein, accordingly, a carrying action is prepared. 30 This action occurs already during the adding operation for which reason the arrow is drawn within the adding range. The circle at the arrow indicates from which denominational order the carrying impulse originates, while the pointed head of the arrow shows the order in which tens carrying is prepared. When, now, the tens carrying action is being effected, the first five step disks in 35 the known step tens carrying device (Fig. 6a) remain ineffective, and only the sixth disk initiates at the proper time the carrying motions which run through the series of wheels up to the highest denominational order whereupon an impulse is transferred to the lowest denominational order and, during the second transfer action, continues its run till the entire tens carrying operation is completed. During the second series of 40 continued tens carrying actions the wheel of the orders 6 to 10 are ineffective. Thus during the two series of carryings each of the carrying wheels remain once ineffective, that is, altogether 45 one series of subsequent carrying motions were ineffective.

50 In the arrangement according to Fig. 6a' immediately from the start of the carrying motions tens carrying is completed in the sixth order in which tens carrying was prepared during the adding operation, to begin with. Thereby the waste of time (idle running of the first five disks) experienced when the normal step arrangement is employed, is dispensed with, and the tens carrying actions are done already at the end of the first series of carrying motions, so that there is no need for a second series of such motions. As in connection with an adding or subtracting operation never more than one tens transfer impulse in each order is originated, the example illustrates the highest efficiency of the tens carrying as it occurs in each denominational order.

55 As the second example:

$$160,570 \text{ minus } 520,700$$

60 is to be balanced (Figs. 6b and 6b'). At this time the wheels are adjusted:

$$\begin{array}{r} (+) 0 \ 000 \ 160 \ 570 \\ (-) 9 \ 999 \ 839 \ 429 \end{array}$$

When the amount 520,700 is entered onto the subtract wheels, in the third and sixth order tens carrying to the fourth and seventh order (see the arrows in the direction indicating adding operations) is prepared. In the known device completing the tens carrying starts from the fourth carrying disk, the first three disks remaining ineffective, and the idle run of the six step disk causes a further delay (Fig. 6b), while in the new device (Fig. 6b') tens carrying is completed immediately and simultaneously in the two denominational orders prepared for tens carrying, and is continued without any interruption.

65 The simultaneous carrying prepared in all orders, is illustrated the most clearly by the third example (Figs. 6c and 6c'):

$$\begin{array}{r} (+) 0 \ 000 \ 000 \ 000 \\ (-) 111 \ 111 \ 111 \end{array}$$

70 where thus the amount 111,111,111 is to be entered subtractively into the balance totalizer standing at zero. The add and subtract wheels are in this instance adjusted so as in connection with the first problem. By adding the said amount on the subtract wheels, in each denominational order tens carrying is caused. The carrying operations are effected in the known device without any connections to one another, while with the device according to the invention 75 said operations occur simultaneously in all the denominational orders, besides the lowest one where the fugitive "one" is added by the second tooth of the carry mechanism actuating pinion.

80 In connection with the last example it may be mentioned that the transfer mechanism is strained to the most by the tens carrying actions simultaneously caused in all denominational orders. As in all denominational orders an effective part of the carry mechanism actuating pinion is present during the whole time of a tens transfer, i. e. during the whole revolution of the shaft 20, said available time period can be subdivided into any number of steps as desired. The carrying wheels according to another embodiment (Fig. 7) of the invention, can be arranged 85 in such a way that the carrying operations in some of the individual denominational orders may be delayed. In a balance totalizer comprising ten denominational orders, the carry mechanism operating pinion can be provided with a gap 90 between the first and tenth tooth and the wheels of the first five orders are arranged in staggered position relative to the last five orders, so that the first working tooth of the first orders is positioned ahead of the first tooth of the last five 95 orders.

100 Another way to obtain this result is that the pinions of the first five orders are provided with one tooth more than there are denominational orders provided in the balance totalizer. In this case the first five pinions have eleven teeth (Fig. 3), and the last five pinions ten teeth each, the said pinions being so disposed on the carry actuating shaft that the first tooth of the last pinion and the second tooth of the first pinion become 105 effective at the same time whereupon the time period for distributing the carrying motions is twice as long as in the first embodiment.

110 The pinions provided with a gap can be arranged alike in all the odd denominational orders and with the first tooth ahead in all even orders. In the odd or even orders pinions having eleven teeth in lieu of ten teeth in the other orders can be arranged with a balance totalizer of ten orders.

While the form of mechanism herein shown and described, is admirably adapted to fulfill the objects primarily stated, it is to be understood that it is not intended to confine the invention to the embodiments herein disclosed, for it is susceptible of embodiment in various other forms all coming within the scope of the claims which follow.

What is claimed as new is:

- 5 1. In a tens transfer mechanism for a totalizer having a plurality of denominational elements, the combination of tens transfer entering means interposed between adjacent denominational elements; means on each totalizer element to preliminarily set its associated tens transfer entering means as the totalizer passes through zero; a gear associated with each tens transfer entering means for actuating the tens transfer entering means after the latter have been preliminarily set to enter one unit in the next higher totalizer element said gears each having as many teeth as there are denominational elements in the totalizer the space between the first and the last teeth being greater than the space between the other teeth; and means to rotate the gears one complete rotation for each operation of the machine to enter all tens transfers during one rotation of the gears.
- 10 2. In a transfer mechanism for a totalizer having a plurality of denominational orders, the combination of tens transfer means between the various denominational orders, and a transfer actuating gear in each denominational order, the actuating means of which in one order is effective variably with respect to the actuating means on a gear of another order to actuate the tens transfer means upon passage of a denominational

order through zero, thus distributing the entering load throughout a single cycle.

3. In a transfer mechanism for a totalizer having a plurality of denominational orders, the combination of tens transfer means between the various denominational orders, and actuating means cooperating with the tens transfer means differently in each order to prevent overloading when more than one transfer means is operated simultaneously.

4. In a transfer mechanism for an add and subtract totalizer having several denominational orders, the combination of a tens transfer means; a shaft performing one revolution in each machine operation; and gears provided with as many teeth as denominational orders in said totalizer and with a gap between the first and the last teeth, one of said gears being arranged on said shaft in each denominational order with the gaps in the various gears staggered in certain of said orders to actuate the transfer means in staggered timing.

5. In a tens transfer mechanism for an add and subtract totalizer having several denominational orders, a tens transfer means; a tens carry actuating shaft performing one rotation during each machine operation; gears provided with as many teeth as denominational orders in said totalizer and a gap between the first and the last teeth, said gears being arranged on said shaft in some of the denominational orders; and gears having one tooth more than the denominational orders in said totalizer, and arranged on the shaft in the remaining denominational orders, said gears provided to actuate the tens transfer means in successive timing.

ERNST BREITLING.
